RADIATOR CONSTRUCTION

Richard H. Nelson, Moline, Ill., assignor to The Herman Nelson Corporation, Moline, Ill., a corporation of Illinois

Application March 16, 1932, Serial No. 599,139

14 Claims. (Cl. 257—136)

This invention relates to improvements in radiator construction.

The radiator of the present invention is intended primarily for use in cabinets recessed in or set on legs near the walls of the room with an intake at or near the floor and a discharge into the room at a higher level, and the present radiator is designed in particular to conform to the requirements of cabinets of the character mentioned, although it may be used under other circumstances.

With this end in view, the radiator of the present invention is of generally rectangular shape and of comparatively shallow dimensions, and in order to permit the radiator to be located in close proximity to the floor to get the maximum flue effect and to obviate the waste of space necessary for adding externally connected valves for controlling the inflow and outflow of the heating medium, the radiator is constructed with relatively large headers within which the valves are housed, provision being made for the manipulation of the inlet valve from a point outside of the cabinet and within easy reach of a person in the room.

The radiator furthermore is so designed as to permit it to be constructed in unitary form with the cabinet, and inexpensively assembled by specialists at the factory, so that the usual expensive work attending the installation by tradesmen in connection with the heating system of the building is reduced to a minimum; and in order to accommodate the radiator connections to variations in the positioning of the piping, a flexible pipe connection is provided, which may be quickly bent or adjusted to compensate for such variations.

In the usual construction, considerable space is required at the ends of the radiators, or below, for valves and piping connections. Vertical space is valuable, because the cabinets are usually installed under low windows, and raising the bottom of the radiator for valve space reduces the capacity of the radiator for heating by the shortening of the flue height available for drawing air past the heating surfaces of the radiator, and it is with due regard to the above requirements that the present radiator is designed.

In order to fully set forth the characteristics of the radiator construction of the present invention, it is shown in combination with the other contributing features constituting the complete unit recessed in a wall of a room, although it will be understood that the invention is directed primarily to the radiator itself, or to any combination of a radiator within a cabinet where saving of space at the ends or below the radiator is available.

In the drawings:

Figure 1 is a front elevation of a recessed type

of cabinet positioned within a wall recess, with one of the ends partially broken away to reveal the interior;

Fig. 2 is a sectional elevation taken on line 2—2 of Fig. 1, showing the valve, the valve handle extension, and gearing;

Fig. 3 is a sectional plan view of the radiator and valves in the headers taken on line 3—3 of Figure 1;

Fig. 4 is a sectional elevation of the radiator and headers; and

Fig. 5 is a sectional detail through one of the headers, showing one of the valves and connections for the admission of a restricted flow of steam to the radiator.

The cabinet shown in the drawings is designed to fit into a recess 10 in a wall 11, which is of proper depth to accommodate the entire structure.

The cabinet comprises end walls 12, a top wall 13, a back wall 14, and a front panel 17. The cabinet is provided with an inlet 24 in the base, and an air discharge opening 18 near the top of the front panel.

It is to be understood, however, that the radiator of the present invention is equally applicable to a cabinet structure set on the floor out in the room.

The cabinet or housing serves as an enclosure for a radiator comprising an oversize inlet header 27 and a return header 28 (Figs. 3 and 4), each of which is of generally rectangular formation and of a depth and length to extend from the front panel to the rear wall of the cabinet near the end thereof and close to its bottom and above the air inlet 24.

The headers are connected on each side by metal strap bars 29—29, which rigidly unite the two headers and afford a self-sustaining frame structure irrespective of the radiator tubes, which frame structure also affords a base or foundation for the cabinet, which may be secured thereto in any suitable manner, so that the entire assembly can be shipped from the factory as a unit ready to install in position.

The headers are connected by a group of radiator tubes 30 (three in number in the structure shown), which tubes carry a multiplicity of radiating fins 31 which are apertured to permit the passage of the tubes therethrough and are provided with flanges 32 around the apertures, which function as spacers for maintaining the fins at a proper distance from one another and also serve to afford a close metal to metal contact between the fins and the tubes.

Each tube has each of its ends entered into a tube plate 33, which forms a part of the contiguous header, and, as shown, each of the tubes, near one of its ends, is provided with a bellows-folded section 34, which affords an area adaptable

to take up the individual expansion and contraction of the respective tubes under varying thermal conditions.

Heretofore, attaching valves to cabinet covered radiators has been wasteful of space needed for other purposes. For instance, if the valves were placed above the radiator, it has been difficult to pipe from below, and provide access doors for the workmen's tools and get the required space when installed under low windows. If the valves were extended out from each end of the radiator, it reduced the available heating length of the radiator for the same wall space materially, and if the valves were installed below the radiator, it was necessary to shorten the flue height used to draw air through for heating in order to get space to offset the pipes to meet roughed-in branches, and danger of gurgling from accumulation of water above a throttled valve seat was unavoidable.

20 The valves of the present invention are built into the header to avoid the above mentioned space-wasting practices and get the valve seat above the drain level of the radiator tubes and provide space for piping to variably located branch pipes thereof, insuring a minimum piping to variably located branch pipes thereof and insuring a minimum height for the radiator above the floor level.

30 The valve apparatus requires extra room in the header, and the result is increased volumetric header capacity for expanding the steam and means for insuring equal distribution of steam to each heating tube without restriction at the entrance of the tubes, as has heretofore been the case.

35 The inlet header 27 is preferably provided with a valve head 35, which is adapted to be advanced or retracted by the rotation of a screw stem 36 carrying a driven bevel gear 37, which meshes with a bevel gear 38 at the inner end of an adjoining rod 39, which is journalled through a bearing box 40 carried by the header 27, and extends outwardly through the front panel of the housing and carries a handle 41 which permits the valve to be adjusted from a convenient position near the bottom of the front panel, by a person in the room.

40 The valve head coacts with an interchangeable valve seat 42, which as shown is in the form of a removable tail piece 43 extending to above the drain level of the radiator tubes and threaded upwardly through the base of the header, and provided with a restricted aperture 44 adapted to be controlled by the regulation of the valve in proportional restriction according to the amount the valve seat is raised. This arrangement affords an interchangeable variable valve restricted port, close to the drain level, for the inflow of steam, which is desirable in order to get 45 full benefit of the valve regulation and to prevent danger of gurgling or crackling from water accumulation by eliminating space for any aforesaid accumulation of water.

46 The restricted port 44 is a necessity to get ideal 50 equable distribution of steam to scattered radiators of various sizes and distances from the steam generator in the system, by interchanging various sizes until results are acquired.

55 It is usual to employ large pipes up to each radiator to insure freedom from stoppage by scale and dirt, reduce the need of excessive care and skill in layout design for pitch and drainage, and keep the pressure drop from the boiler low to the immediate entrance to each radiator, where a radical restriction is provided for choking the

supply of steam close to the radiator. In the radiator of the present invention, the steam, after passing the orifice 44, will expand in the large header, so that if only enough steam is generated to fill half of the radiators, each one will get its share.

60 The return header 28 is preferably provided with a thermal bellows trap 46 to drain condensed water as fast as formed, but may in lieu thereof be similarly equipped with a hand manipulated valve like the supply header described in detail.

65 Steam is preferably admitted to the inlet header 27 and the water of condensation carried away from the return header 28 through soft flexible copper tubing 45 adapted to be bent and coupled to the roughly put in branch piping installed during early building operations, before exact positions of wall finishes and floor are established, and in view of the fact that the flexibility is afforded by the tubing 45, it is not necessary that the branch pipes be exactly located, or that a radiator be furnished having exact predetermined relation thereto in order to provide for a proper installation of the radiator unit assembly.

70 The arrangement is one which obviates the necessity for elevating the radiator sufficiently to provide for the location of both valves and piping offsets between the headers and the floor level.

75 By location of the valves integral within the headers and shipping the flexible pipe connections complete as an assembled unit that may be installed after all building operations are practically completed, the structure as a whole is greatly simplified and the work of installation 80 materially reduced, so that the radiator as a whole is compact, rugged, efficient, and adapted to be used as a universal unit to fit into the building with very little preparatory supervision, that has heretofore been a burden to both heating and building contractors and architects.

85 Although the radiator has been described in its specific relationship to the cabinet as a whole, nevertheless, it will be understood that the present invention is directed to the details of construction of the radiator in combination with valves and pipe connections rather than to the cabinet as a whole, since the radiator valve combination might be used with advantage in cabinets of different types which omit several of the special 90 features of construction shown.

95 I claim:

1. A radiator comprising spaced headers and tubes between the headers, a restricted orifice steam supply piece in one of the headers, and a valve operable from the exterior of the header and adapted to proportionately vary the effective orifice port by movement of the valve towards or away from its seat.

100 2. In a cabinet radiator, the combination of a cabinet, a radiator with headers one at each end of the cabinet, removable steam supply and return valve mechanisms in the respective headers, a bevel gear operating extension to the exterior of the cabinet for operating the steam supply valve, and thermostatically operated mechanism in the interior of the return header for regulating the return valve.

105 3. In a cabinet radiator, the combination of spaced headers and tubes between the headers, one of the headers being provided with a connection for the inlet of steam, and being provided on its interior with a valve member coacting with a restricted orifice above the drain level of the tubes to vary the discharge through said orifice.

- and controllable by hand, and a thermostatically operated valve mechanism in the return header to drain accumulated condensed water from the radiator.
5. In a radiator, the combination of spaced headers and tubes between the headers, one of the headers being provided with a connection for the inlet of steam, and being provided on its interior with a valve seat member communicating with the inlet and having a restricted aperture for the discharge of steam into the interior of the header for distribution through the tubes, and said apertured member extending above the drain level of the tubes.
10. In a radiator, the combination of spaced headers and tubes between the headers, one of the headers being provided with a connection for the inlet of steam, and being provided on its interior with a member communicating with the inlet and having a restricted aperture for the discharge of steam into the interior of the header for distribution through the tubes, and a valve within said header adapted to vary the restriction of said aperture to efficiently control the discharge of steam through said apertured member.
15. In a radiator, the combination of spaced headers and tubes between the headers, one of the headers being provided with a connection for the inlet of steam, and being provided on its interior with a member communicating with the inlet and having a restricted aperture for the discharge of expanded steam into the interior of the header for distribution through the tubes, the said apertured member extending above the drain level of the tubes, and a valve within said header adapted to control the discharge of steam through the aperture of said member.
20. In a radiator, the combination of horizontally elongated spaced headers and substantially horizontal tubes between the headers, one of the headers being provided through its bottom with a transversely opening vertically extending connection for the inlet of steam, and being provided on its interior with a vertically operable valve, said valve including a vertically extending valve stem provided at its upper end with a bevel gear, and a handle and horizontal shaft provided at its inner end with a bevel gear meshing with the first named bevel gear for controlling the valve from an accessible point, and reinforcing bars connecting the headers for protecting the tubes against distortion.
25. In a radiator, the combination of spaced headers and tubes between the headers, one of the headers being provided with a connection for the inlet of steam, and being provided on its interior with a removable member communicating with the inlet, and having a restricted aperture for the discharge of steam into the interior of the header for distribution through the tubes, and said apertured member extending above the drain level of the tubes, and a valve within said header adapted to control the discharge of steam through the aperture of said member, said valve including a valve stem provided at its upper end with a bevel gear, and a handle and shaft provided at its inner end with a bevel gear meshing with the first mentioned bevel gear for controlling the valve from an accessible point.
30. In a radiator, the combination of a pair of spaced headers and connecting tubes having fins threaded thereonto, each of the headers being of transversely elongated form, and connecting bars secured to the ends of the headers and embracing and protecting the fins mounted thereon and serving to reinforce the structure independently of the tubes, one of the headers being provided with a hand controlled inlet valve and the other header with a thermostatically operated discharge valve, the inlet header being provided with a removable tail piece having a restricted orifice for steam and extending above the discharge level of the tubes, a flexible supply pipe registering with said tail piece, and a coupling for holding the parts in assembled relation, the inlet valve co-acting with said tail piece, and means for regulating said valve and the restrictive effect of said orifice from a point outside of the header.
35. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
40. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
45. In a radiator, the combination of spaced headers and tubes between the headers, a steam supply valve head structure adapted to be vertically screwed in as a complete assembly and located within the inlet header, and supply and return pipe connections for the respective headers.
50. In a radiator, the combination of spaced headers and tubes between the headers, a steam supply valve head structure adapted to be vertically screwed in as a complete assembly and located within the inlet header, and supply and return pipe connections for the respective headers.
55. In a radiator, the combination of spaced headers and tubes between the headers, a steam supply valve head structure adapted to be vertically screwed in as a complete assembly and located within the inlet header, and supply and return pipe connections for the respective headers.
60. In a radiator, the combination of spaced headers and tubes between the headers, a steam supply valve head structure adapted to be vertically screwed in as a complete assembly and located within the inlet header, and supply and return pipe connections for the respective headers.
65. In a radiator, the combination of spaced headers and tubes between the headers, a steam supply valve head structure adapted to be vertically screwed in as a complete assembly and located within the inlet header, and supply and return pipe connections for the respective headers.
70. In a radiator, the combination of spaced headers and tubes between the headers, a steam supply valve head structure adapted to be vertically screwed in as a complete assembly and located within the inlet header, and supply and return pipe connections for the respective headers.
75. In a radiator, the combination of spaced headers and tubes between the headers, a steam supply valve head structure adapted to be vertically screwed in as a complete assembly and located within the inlet header, and supply and return pipe connections for the respective headers.
80. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
85. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
90. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
95. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
100. In a device of the class described in combination with fixedly located branch piping, the combination of a radiator comprising separated headers and connecting tubes provided with fins, reinforcing bars connecting the ends of the headers and extending outside of the fins, supply and return pipes connected with the respective headers and with the fixed branch piping, one of said pipes being flexible, and a boxlike cabinet enclosing the radiator and rigidly secured thereto to constitute a unit in conjunction therewith, the radiator being located near the base of the cabinet and constituting a frame therefor.
105. In a radiator comprising spaced inlet and return headers and tubes between the headers, a steam supply valve head structure adapted to be vertically screwed in as a complete assembly and located within the inlet header, and supply and return pipe connections for the respective headers.
110. In a radiator comprising spaced inlet and return headers and tubes between the headers, a steam supply valve head structure adapted to be vertically screwed in as a complete assembly and located within the inlet header, and supply and return pipe connections for the respective headers.
115. In a radiator comprising spaced inlet and return headers and tubes between the headers, a steam supply valve head structure adapted to be vertically screwed in as a complete assembly and located within the inlet header, and supply and return pipe connections for the respective headers.
120. In a device of the class described, the combination of a radiator comprising separated headers and connecting tubes, provided with sections configured to take up the individual expansion and contraction of the respective tubes under varying thermal conditions, fins carried by the tubes, reinforcing bars rigidly connecting the headers, and supply and return pipes connected with the respective headers, one of said pipes being flexible, said supply and return pipes being adapted for connection with the fixedly located piping of a building.
125. In a device of the class described, the combination of a radiator comprising separated headers and connecting tubes, provided with sections configured to take up the individual expansion and contraction of the respective tubes under varying thermal conditions, fins carried by the tubes, reinforcing bars rigidly connecting the headers, and supply and return pipes connected with the respective headers, one of said pipes being flexible, said supply and return pipes being adapted for connection with the fixedly located piping of a building.
130. In a radiator, the combination of spaced inlet and return headers having on all sides elongated side walls and having closing end walls, tubes extending between the headers and entered into the opposed inner side walls, a connection for the inlet of steam entered into one of the other side walls of the inlet header on an axis substantially at right angles to the axis of the tubes, a head structure for the discharge of steam, located within the inlet header and constituting an interior extension on the steam connection and extending in the same direction and adapted to discharge steam transversely of the header, a transversely movable interior valve adapted to control the discharge from said head structure, and a transversely extending valve stem extending from said valve through the opposite side wall of the header and adapted to be operable from an exterior position, and a return pipe leading from the return header.
135. In a radiator, the combination of spaced inlet and return headers having on all sides elongated side walls and having closing end walls, tubes extending between the headers and entered into the opposed inner side walls, a connection for the inlet of steam entered into one of the other side walls of the inlet header on an axis substantially at right angles to the axis of the tubes, a head structure for the discharge of steam, located within the inlet header and constituting an interior extension on the steam connection and extending in the same direction and adapted to discharge steam transversely of the header, a transversely movable interior valve adapted to control the discharge from said head structure, and a transversely extending valve stem extending from said valve through the opposite side wall of the header and adapted to be operable from an exterior position, and a return pipe leading from the return header.
140. In a radiator, the combination of spaced inlet and return headers having on all sides elongated side walls and having closing end walls, tubes extending between the headers and entered into the opposed inner side walls, a connection for the inlet of steam entered into one of the other side walls of the inlet header on an axis substantially at right angles to the axis of the tubes, a head structure for the discharge of steam, located within the inlet header and constituting an interior extension on the steam connection and extending in the same direction and adapted to discharge steam transversely of the header, a transversely movable interior valve adapted to control the discharge from said head structure, and a transversely extending valve stem extending from said valve through the opposite side wall of the header and adapted to be operable from an exterior position, and a return pipe leading from the return header.
145. In a radiator, the combination of spaced inlet and return headers having on all sides elongated side walls and having closing end walls, tubes extending between the headers and entered into the opposed inner side walls, a connection for the inlet of steam entered into one of the other side walls of the inlet header on an axis substantially at right angles to the axis of the tubes, a head structure for the discharge of steam, located within the inlet header and constituting an interior extension on the steam connection and extending in the same direction and adapted to discharge steam transversely of the header, a transversely movable interior valve adapted to control the discharge from said head structure, and a transversely extending valve stem extending from said valve through the opposite side wall of the header and adapted to be operable from an exterior position, and a return pipe leading from the return header.
